UNITED STATES PATENT OFFICE.

FRANK C. WHITE, OF MERIDEN, CONNECTICUT, ASSIGNOR TO WILCOX & WHITE COMPANY, OF MERIDEN, CONNECTICUT, A CORPORATION OF CONNECTICUT.

AUTOPNEUMATIC MUSIC-PLAYING INSTRUMENT.

No. 852,752.

Specification of Letters Patent.

Patented May 7, 1907.

Application filed October 29, 1906. Serial No. 341,054.

To all whom it may concern:

Be it known that I, FRANK C. WHITE, a citizen of the United States, residing at Meriden, county of New Haven, Connecticut, have invented certain new and useful Improvements in Autopneumatic Music-Playing Instruments, of which the following is a full, clear, and exact description.

My invention relates to improvements in auto-pneumatic music playing instruments. In such devices there is what is ordinarily termed an "action," usually located in what is termed the "wind-chest," in which a reduced pressure is ordinarily maintained during the operation of the instrument. This reduced pressure is accomplished by means of a bellows actuated ordinarily by pedal. Between this bellows, termed the "feeder" and the wind-chest, is located an equalizer bellows, the purpose of which is to equalize the pulsations of the feeder bellows so that the tension in the wind-chest will be substantially uniform. In such apparatus it is desirable at times to produce in the wind-chest a high degree of tension for various purposes, such, for example, as increasing the power applied to the sounding devices. In the ordinary type of instrument this increased tension in the wind-chest is effected by actuating the feeder bellows more energetically, so that a high tension will be attained after several strokes thereof.

The purpose of my invention is to provide a simple, effective and reliable means whereby high tension may be produced instantly in the wind-chest.

In the accompanying drawing I have in a single figure illustrated in section and diagrammatically those parts which are essential to a clear understanding of my invention.

A is the wind-chest.

B is what is termed the feeder bellows, which may be operated by a pedal C; the latter being suitably connected with said bellows, as, for example, by a lever D and link E. A spring F moves the bellows B in opposition to the pedal C.

G is a wind-way leading from the interior of bellows B to the wind-chest A.

H is an equalizer bellows normally expanded by the action of a spring I. This equalizer bellows has a port J which commu-

nicates with the wind-way G. The usual valve K may be provided for the bellows B to 55 permit air to be exhausted therefrom on the collapse of the bellows. L is another valve, which covers the port leading into the wind-way G. By means of these valves air is exhausted from the wind-chest or action A as 60 the bellows B is operated. The equalizer H performs the function usual to such appliances.

M is a throttle or check valve which stands over the port J. Under normal conditions 65 this throttle or check valve M does not unduly obstruct the port J, but as the bellows B is operated it stands in such a position as to permit air to be drawn readily from the equalizer bellows H in the usual manner. 70 Should, however, a quick impulse be imparted to the bellows B in a direction to exhaust the air, the throttle M will close down on the port J so as to practically cut out the equalizer bellows momentarily, with the result 75 that the high tension produced in the feeder bellows B will simultaneously be produced in the wind-chest A, and since this is accomplished instantaneously it is possible for the operator in the rendering of a piece of 80 music to cause selected notes to be attacked with greater vigor than would normally occur when the equalizer is in full action. This, as will be seen, is of substantial advantage, because it permits, without the aid of 85 any appliances for manual operation other than the pedals themselves, the operator to have a greater control of the instrument than would otherwise be possible, and it will even permit the operator to readily bring 90 out solo or melody notes in the rendering of compositions where such effects are desirable without the aid of any supplemental apparatus.

As shown in the drawings, the check valve 95 or throttle M is merely suspended from above by a suitable hinge, so as to hang over the port J. Through this check valve, in the particular form shown, is a bleed-hole M', one or more of which may be provided. 100 In operation, when the operator starts to exhaust air by means of the exhausters B, a reduction in air pressure will occur in the wind-way G as well as in the equalizer bellows H, the latter being collapsed against the 105 expanding action of spring I. This will

occur whether the valve M is against its seat or away from its seat. As soon as the pressure is caused to drop in the wind-way G from any cause, the bellows H will tend to expand, unseating the valve M. While the operator is actuating the exhauster B with substantial uniformity, this valve M will remain unseated, so that the port J will be open to its full capacity and the tension will be equalized by the bellows H in the usual manner. If, however, an abnormal pressure is applied to the pedal C, so as to produce a momentary abnormal vacuum, the same will cause such a suction at the port J as to seat the valve M, momentarily practically cutting out the equalizing effect of the bellows H, whereupon it follows that the higher tension will cause the action pneumatics to operate with a relatively increased power, so as to sound any particular note or notes with greater vigor. By this simple means it is within the power of the operator at any time to emphasize any particular note or notes. One particular advantage of this construction is that it permits the operator to vary what I may term the normal tension, so long as the changes are effected gradually. At the same time, no matter what the tension may be at any particular time, at such time it is within his power, by what would then be an abnormal pressure on the pedal, to cause particular notes to stand out above the others. It should be understood that I regard the bleed-hole tapping into the equalizer bellows H as the preferable way of constructing the apparatus to secure the desired effect.

It is preferable, of course, to have the equalizer bellows in direct communication with the wind-way, although this may not be essential in all cases.

What I claim is:

1. In an auto-pneumatic music playing instrument, a wind-chest or its equivalent, a feeder bellows for exhausting air therefrom, means for manually operating the latter, an equalizer or its equivalent, comprising a single valve for permitting the operator to instantly secure by the abnormal action of the feeder bellows a higher tension in the wind-chest than in the equalizer.

2. In an auto-pneumatic music playing instrument, a wind-chest, a feeder bellows, a wind-way, an equalizer communicating with the wind-way between said wind-chest and feeder bellows, automatic means comprising a check valve controlled by an abnormal operation of the feeder bellows for practically nullifying the effect of said equalizer, and a bleed-hole tapping into said equalizer.

3. In an auto-pneumatic music playing instrument, a wind-chest, a feeder bellows, a wind-way, an equalizer communicating with the wind-way between the wind-chest and

feeder bellows, and means controlled by an abnormal operation of the feeder bellows for practically nullifying the effect of said equalizer, said means comprising a check valve for the passage leading from the wind-way to the equalizer, said valve having a bleed-hole therein registering with said passage.

4. In an auto-pneumatic music playing instrument, an action or wind-chest, a feeder bellows in communication therewith, means for normally equalizing the degree of exhaustion in the wind-chest when the feeder bellows is operating normally, and comprising a single valve controlled by the abnormal action of the feeder bellows for practically nullifying the action of the equalizer.

5. In an auto-pneumatic music playing instrument, an action chest or main exhaust chamber, a feeder or exhaust bellows, a passage leading directly from said exhaust bellows to said exhaust chamber, an equalizer bellows for securing a normal tension in said exhaust chamber, said bellows tapping into the passage leading from the exhaust bellows to the main exhaust chamber but not constituting a part thereof, a check valve for said passage, and a bleed hole or vent for said equalizer.

6. In an auto-pneumatic music playing instrument, a wind-chest, a feeder bellows, a wind-way between the wind-chest and the feeder bellows, an equalizer bellows in communication with the wind-way, means to yieldingly distend the equalizer bellows, and a single valve for permitting the operator to secure, by an abnormal operation of the feeder bellows, a higher degree of tension in the wind-chest than in said equalizer, said valve having a vent therein communicating with the passage which said valve is adapted to close and of smaller area than said passage.

7. In an auto-pneumatic music playing instrument, a wind-chest, a feeder bellows, a wind-way, an equalizer in communication with the wind-way, automatic means comprising a check valve controlled by an abnormal operation of the feeder bellows for practically nullifying the effect of the equalizer, and a vent or bleed hole tapping into said equalizer.

8. In an auto-pneumatic music playing instrument, a wind-chest, a feeder bellows, a wind-way, an equalizer communicating with the wind-way, means controlled by the abnormal operation of the feeder bellows for practically nullifying the effect of said equalizer, said means comprising a check valve for the passage leading to the equalizer, and a bleed hole or vent through said valve and registering with said passage.
